(57) CLAIM

The ornamental design for a packing box for trash bag, as shown and described.

DESCRIPTION

FIG. 1 is an exploded front perspective view of a packing box for trash bag showing my new design;

FIG. 2 is an exploded right side view thereof;

FIG. 3 is an exploded left side view thereof;

FIG. 4 is a top view thereof; and,

FIG. 5 is a bottom view thereof.

The broken lines shown in the figures represent portions of the packing box for trash bag that form no part of the claimed design.
